CLAIM

The ornamental design for a handle for scissors, as shown and described.

DESCRIPTION

FIG. 1 is a perspective view of the first embodiment of a handle for scissors showing my new design;

FIG. 2 is a top view thereof;

FIG. 3 is a bottom view thereof;

FIG. 4 is a back view thereof;

FIG. 5 is a front view thereof;

FIG. 6 is a right side view thereof;

FIG. 7 is a left side view thereof;

FIG. 8 is a perspective view of the second embodiment of a handle for scissors;

FIG. 9 is a top view thereof;

FIG. 10 is a bottom view thereof;

FIG. 11 is a back view thereof;

FIG. 12 is a front view thereof;

FIG. 13 is a right side view thereof; and,

FIG. 14 is a left side view thereof.

In the drawings, the broken lines are for the purpose of illustrating environment only and form no part of the claimed design.

1 Claim, 5 Drawing Sheets
